UNITED STATES PATENT OFFICE

CHARLES H. SLAUTER, OF COLUMBUS, OHIO

GAS BURNER

Application filed May 13, 1927. Serial No. 191,204.

This invention relates to improvements in gas burners and has for its primary object the provision of a gas burner adapted to promote uniform and complete combustion of the gaseous fuel utilized thereby, to produce a burner characterized by its odorless operation and a burner wherein provision is made for securing an intimate and thorough mixture of the fuel with the oxygen of the air to permit of the production of a highly efficient flame of green, violet and blue appearance.

Another object of the invention resides in the provision of a burner formed to comprise a V shaped frame which is secured to a gas conduit having an orifice in the upper end thereof, the diverging arms of the frame being shaped to support in a horizontal plane, disposed axially above the orifices in said conduit, a flat deflector plate, against the under surface of which the gas stream is directed under pressure, whereby the impingement of the gas stream upon the under surface of the plate serves to break up the stream and to permit of the intimate commingling of the air therewith, enabling active combustion to take place contiguous to the peripheral edge of the plate. A further object of the invention resides in forming the supporting frame for the plate so that said frame will not interfere with the combustion taking place around the peripheral edge of the plate.

For a further understanding of the invention reference is to be had to the following description and the accompanying drawing wherein:

Figure 1 is a vertical sectional view taken centrally through the improved burner comprising the present invention,

Figure 2 is a perspective view of the deflecting plate and its supporting frame,

Figure 3 is a vertical sectional view of a modified form of the invention,

Figure 4 is a horizontal sectional view taken on the line 4—4 of Figure 3.

Referring more particularly to the drawing the numeral 1 designates an upstanding pipe or conduit through which is led gas, either natural or artificial, under pressure.

The upper end of the pipe or conduit is substantially closed and is provided axially with a threaded port for the reception of a removable tip 2 in which is provided a gas orifice 3, which may be of any appropriate diameter depending upon the kind of gas employed and also the pressures utilized. One of the features of the invention resides in enabling the burner to operate with tips possessing orifices of varying area, the burner permitting of efficient combustion regardless of the artificial diameter of the gas port which may be selected, although for best economy and efficiency tips of certain selected area are to be desired.

In this instance, the outer part of the pipe 1, adjacent to its upper end, is threaded for the reception of spaced binding nuts 4 which are utilized to receive and hold the lower end of a substantially V shaped frame 5 in connection with the pipe. This frame comprises downwardly extending converging arms which are substantially triangular in cross-section, the lower ends thereof terminating in a circular web 6 which is provided with an opening for the accommodation of the pipe 1, and through the medium of the nuts 4 the frame can be rigidly held in its operative position. The upper ends of the frame arms terminate in horizontally and inwardly directed portions 7, which, in turn, terminate in downwardly and vertically directed legs 8, the lower ends of said legs being in this instance integrally formed with a horizontally arranged, circular deflecting plate 9, which is arranged in a horizontal plane disposed at an appropriate distance above the pipe 1 and in axial relation with respect thereto.

By this arrangement it will be seen that the gas stream issuing in a thin long attenuated stream under pressure and at relatively high velocity from the orifice 3 strikes upon the lower axial portion of the plate 9 and is violently agitated and moved in turbulent eddying waves toward the outer peripheral edge of the deflecting plate. While in this relatively violent stage of agitation the gas is actively commingled with oxygen drawn freely from the atmos-

phere so that a combustible mixture of highly efficient proportions is produced which permits combustion to take place around the peripheral edge of the disk or plate. In fact, in the operation of the burner there are no visible evidences of combustion in planes below the under surface of the disk or plate, combustion apparently not taking place until the gases have 5 passed the peripheral edge of the disk and are in course of ascension. The color of the flames of combustion is indicative of efficient operation in that the flames take on a vari-colored appearance of blue, violet 10 and green, being a pronounced blue when the operation of the burner is initiated and then producing the light green shades after the burner has been in operation for a short time and the disk or plate heated, however, the heating of the disk is not essential 15 in procuring effective operation. The burner has the advantage of the usual Bunsen type of burner but has no tendency to flash out or to burn back in the mixer if the gas pressures fluctuate, thereby lending itself admirably for use in heating devices wherein 20 thermostatic controls are provided. Again, through the construction of the device it is not necessary to use screens or the like 25 for preventing the gas mixtures from burning at the proper points, inasmuch as fluctuation of pressures and volumes in the gas stream will not produce uniform combustion. 30

In the modified form of the invention disclosed in Figures 3 and 4, the upper end 35 of the pipe 1 has connected thereto a disk 10, to which is secured a plurality of up-standing legs 11 which support a circular plate 12 in spaced relation above the upper 40 end of the pipe 1. In connecting the legs 11 near the central portion of the plate 12 the intense heat of the flame will not come into direct contact with the legs 11 and thereby prevent the same from burning off, 45 sagging or warping.

What is claimed is:

1. In a burner of the character described, a circular flat plate, a gas conduit having a restricted gas flow orifice therein situated 50 in spaced relationship from said plate to direct a gas stream upon the axial portion of said plate, and a support for said plate connected to the upper surface thereof whereby the under surface and edge of said 55 plate are left free and unobstructed to the gas stream flowing in all directions toward said edge.

2. In a burner of the character set forth, a circular plate, a gas conduit having a 60 restricted gas flow orifice therein situated in spaced relationship from said plate to direct the gas stream upon the axial portion of said plate, said plate being so supported as to leave the under surface and edge 65 thereof free and unobstructed to the gas

flowing radially in all directions under said plate.

In testimony whereof I affix my signature.

CHARLES H. SLAUTER.
